(57) **CLAIM**

The ornamental design for a wall bracket, as shown and described.

DESCRIPTION

FIG. 1 is a perspective view of a wall bracket, showing my new design;

FIG. 2 is another perspective view thereof;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view of the wall bracket in an expanded state; and,

FIG. 10 is another perspective view thereof.

The broken lines shown in the drawings illustrate portions of the wall bracket that form no part of the claimed design.

1 Claim, 10 Drawing Sheets
